UNITED STATES PATENT OFFICE.

WALTER S. HILDEBRAND, OF MOUNT UNION, PENNSYLVANIA.

MEANS FOR FILLING MOLDS.

Application filed February 16, 1921. Serial No. 445,423.

To all whom it may concern:

Be it known that I, WALTER S. HILDEBRAND, a citizen of the United States, residing at Mount Union, in the county of Huntingdon and State of Pennsylvania, have invented certain new and useful Improvements in Means for Filling Molds, of which the following is a specification.

The invention relates to improvements in mold filling mechanisms, and more particularly to a type of such mechanisms adapted for use in the making of silica brick for the construction of coke ovens, steel works, and the like.

15 In the present practice of making bricks of the character mentioned, the methods for the filling of the brick molds, which are substantially rectangular in form, have certain serious disadvantages and defects,—caused 20 primarily by the formation of air pockets along the angular edges and corners at the bottom of the molds by reason of the silica mud not being sufficiently packed or otherwise entirely filling the mold, so that the 25 resultant bricks have their edges formed on broken or ragged lines and not in the nature of smooth angular surfaces, as is desired. These disadvantages and defects have been overcome heretofore in some instances by 30 jarring the molds or by packing the silica mud into the molds by hand, such as requires an excessive expenditure of time and without any definite assurance that the angles and corners of the molds have been 35 completely filled.

The principal object of the present invention, therefore, is to provide a mechanism of the type set forth, whereby to overcome the serious defects and disadvantages aforesaid, 40 and one which is entirely automatic in operation, the same embodying a means for delivering a slightly excessive amount of silica mud in a form to drop by gravity into a mold where natural spreading action under 45 its own weight will cause the latter to be completely filled without any possibility of air pockets being formed in the resultant rectangular mass in the same.

With the foregoing and other objects in 50 view, the invention resides in the certain new and useful construction, and arrangement of parts, as will be hereinafter more fully de-

scribed, set forth in the appended claims, and illustrated in the accompanying drawings, in which:—

Fig. 1 is a top plan view of the feed hopper,

Fig. 2 is a side elevation thereof,

Fig. 3 is an end elevation of the same,

Fig. 4 is a vertical transverse section taken 60 on the line 4—4 of Fig. 1, showing a measured charge of the silica mud in position to be discharged to the mold,

Fig. 5 is a view similar to that of Fig. 4, but showing the mechanism adjusted for a 65 larger charge of the silica mud in position to be discharged to the mold,

Fig. 6 is a view similar to that of Figs. 4 and 5, but showing the position of the charge measuring and delivering means after a 70 charge of the silica mud has been discharged to the mold,

Fig. 7 is a fragmentary detail of the automatic actuating means for the charge delivery mechanism,

Fig. 8 is a diagrammatical view of the 75 entire mechanism positioned for operation, and,

Fig. 9 is a vertical, longitudinal section 80 through one of the brick molds of conventional form.

Referring to the drawings, wherein similar characters of reference designate corresponding parts in the several views thereof, the numeral 10 designates generally a hopper having oppositely inclined walls 11, spaced apart at their lower edges to provide a longitudinally extending opening 11' therebetween medially of the hopper and its opposite end walls 12 depending for a distance 85 below the bottom walls 11.

Extending to either side of the opening 11' in both of the side walls 12 are pairs of horizontally elongated slot-ways 13 and 13', in which are slidably supported a pair of rods or shafts 14 and 14' to each of which is dependingly secured rectangular plates 15 and 15', respectively, which are normally held with their bottom edges in close abutting relation on a line in the plane of the longitudinal center of the opening 11' and forming between their opposed faces a substantially V-shaped discharge hopper, each of the plates being provided with outwardly

projecting arms 16 and 16', respectively, on which are carried weights 17 and 17', respectively, for such purpose.

The shafts 14 and 14' each have their oppositely projecting ends supported in journaled carriages 18 and 18', respectively, which have sets of rollers 19 and 19', operating on rails 20 one on either side of the hopper 10. For adjusting the plates 15 and 15' one with respect to the other, whereby to vary the capacity of the discharge hopper formed by and between the same, the carriages 18 at one side of the main hopper 10 are inter-connected together by means of a pair of links 21 and 21', pivotally connected at their free ends to an actuating link 22 to form a toggle mechanism. The link 22 is formed to provide an interiorally threaded eye 23 in which is engaged the threaded shaft 24 which is, in turn, journaled in a bearing bracket 25 secured to the outer face of one of the side walls 12 of the hopper 10 and has its lower free end provided with a hand wheel 26 for its operation. The eye 23 on the link 22 is formed with a laterally projecting indicating pointer 27 which is movable over a scale 28 laid out on the face of the hopper wall 12 in parallel relation to the longitudinal axis of the screw-threaded shaft 24, whereby the capacity of the discharge hopper formed by the plates 15 and 15' may be accurately adjusted for the filling of particularly sized molds. By turning the hand wheel 26 in one direction, the pairs of carriages 18 and 18' are moved toward each other and in a reverse direction, away from each other, and the shafts 14 and 14' are moved correspondingly along the slot-ways 13 and 13', whereby to correspondingly move the upper portion of the plates 15 and 15' toward each other, or away from each other, as the case may be.

For the purpose of opening the plates 15 and 15' in a rapid manner for the discharge of a charge of silica mud therefrom, on the outer side of the same are formed closed loop members 29 and 29', respectively, having their slotted openings elongated in a vertical direction, and extending transversely of the hopper 10 and passing through the loop members 29 and 29' are a pair of shafts or rods 30 and 30', respectively, the opposite ends of the same being engaged in pairs of slots 31 and 31', formed in the side walls 12 of the hopper 10. Carried on the outer ends of the shafts 30 and 30' are rollers 32 and 32', respectively, and operated with one pair of these rollers 32 at one side of the hopper 10 is a substantially triangular-shaped cam member 33, which is carried on an arm 34 extending to one side of the hopper 10.

Referring particularly to Figs. 7 and 8, the outer end of the arm 34 is loosely carried on a driven shaft 35, on which is secured a

sleeve 36 having a slot 37 extending substantially for one-half of its circumference, and in which is engaged a lug 38 carried on the arm 34. Power being applied to the shaft 35, the sleeve 36 is rotated in an anti-clockwise direction, as shown, and the rear end of the slot 37 engages a lug 38 when the arm 34 is depending downwardly from the shaft 35 and swings the same upwardly. As the arm 34 passes the vertical of its upward movement, its downward movement in the further direction of its movement is accelerated by gravity and it falls with great force to its lower position by reason of the lug 38 being now free to traverse the slot 37. In its downward movement, the cam 33 passes between the rollers 32 and forces the same apart, or outward of the slots 31 and 31', whereby the plates 15 and 15' are separated at their lower edges as the silica mud is free to drop downward therefrom. The provision of the weights 17 and 17' assures of the plates 15 and 15' returning to their normal position.

In the use of the invention thus provided, the plates 15 and 15' are adjusted, as before stated, for the reception of a desired or predetermined amount of the silica mud, which is placed in position to the slot 11' of the hopper 10. The charge of mud now assumes a wedge formation, and when the plates 15 and 15' are separated, as before stated, is discharged downward for a suitable distance into the mold 39, which is placed in proper position for its reception. In falling, the charge of mud retains its shape and the apex of the wedge strikes the center of the bottom wall of the mold 39 and immediately spreads outward to all sides of the same with the great force of its impact, as is shown in Fig. 8, the bulk of the charge gradually filling the entire mold and forcing all air outward thereof, afterward, any surplus of the mud may be suitably scraped off the upper side so as to give the bricks the desired smooth surface when finished. After the filling of the first mold, the operation is to be repeated as described for the first instance. It is to be here noted that when the plates 15 and 15' are rapidly separated, the wedge-shaped mass of mud is instantly released but remains suspended in midair momentarily, and then falls to the mold, apex downward.

It is to be understood that various changes in the detail of construction and arrangement of parts may be resorted to without departing from the spirit and scope of the invention.

Having thus fully described the invention, what is claimed, is:

1. A mold filling mechanism comprising a material feed hopper, means depending from said feed hopper for forming a predetermined amount of the material into a substantially wedge-shaped mass, and means

for actuating said first mentioned means for the discharge of the material, when formed, by gravity therefrom into a mold positioned beneath the hopper.

5 2. A mold filling mechanism comprising a material feed hopper, a discharge hopper carried by said feed hopper and adapted for forming a predetermined amount of the material into a substantially wedge-shaped 10 mass, said discharge hopper being formed of transversely separable parts, and means for separating the parts of said discharge hopper for the gravitating therefrom of the material, when formed, whereby the apex of 15 the wedge shaped mass thereof strikes the bottom wall of a mold positioned beneath the hopper and spreads under the force of its impact to completely fill the interior of the mold without the formation of air 20 pockets within the resultant mass.

3. A mold filling mechanism comprising a material feed hopper, a two-part discharge hopper depending from said feed hopper and adapted for forming a predetermined 25 amount of the material into a substantially wedge-shaped mass, means for adjusting the parts of the discharge hopper to accommodate various amounts of the material, and power means for separating the parts of said 30 discharge hopper for the gravitating therefrom of the material, when formed, whereby the apex of the wedge-shaped mass thereof strikes the bottom wall of the mold positioned beneath the hopper and spreads under 35 the force of its impact to completely fill the interior of the mold without the formation of air pockets within the resultant mass.

4. A mold filling mechanism comprising a material feed hopper, a substantially V-shaped discharge hopper formed to provide 40 separable parts pivotally mounted on and depending from said feed hopper, means for adjusting the pivotal supports of the parts of the hopper in opposite directions one from the other, and power means for separating 45 the parts of said discharge hopper for the gravitating therefrom of the material in substantial V-shaped form, whereby the apex thereof strikes the bottom wall of the mold positioned beneath the hopper and 50 spreads under the force of the impact to completely fill the interior of the mold without the formation of air pockets within the resultant mass.

5. A mold filling mechanism comprising a 55 material feed hopper, a substantially V-shaped discharge hopper formed to provide separable parts pivotally mounted on and depending from said feed hopper, means for adjusting the pivotal supports of the parts 60 of the hopper in opposite directions one from the other, and power actuated cam means for separating said parts of said discharge hopper for the gravitating therefrom of the material in substantial V-shaped 65 form, whereby the apex thereof strikes the bottom wall of a mold positioned beneath the hopper and spreads under the force of its impact to completely fill the mold without 70 the formation of air pockets within the resultant mass.

In testimony whereof, I affix my signature hereto.

WALTER S. HILDEBRAND.
